UNITED STATES PATENT OFFICE.

JAMES F. COLLEY, OF EL PASO, TEXAS.

DESIGN FOR A MEAT-TENDERER.

48,170.

Specification for Design.

Patented Nov. 23, 1915.

Application filed November 4, 1914. Serial No. 870,308. Term of patent 14 years.

To all whom it may concern:

Be it known that I, JAMES F. COLLEY, a citizen of the United States, residing at El Paso, in the county of El Paso and State of Texas, have invented a new, original, and ornamental Design for Meat-Tenderers, of which the following is a specification, reference being had to the accompanying drawing, forming a part thereof.

Figure 1 is a perspective view of one side

of a meat tenderer. Fig. 2 is a perspective view of the opposite side of a meat tenderer showing my new design.

I claim:

The ornamental design for a meat tenderer, as shown.

JAMES F. COLLEY.
